DESIGN.

H. G. FITZ GERALD,

SPOT LIGHT.

APPLICATION FILED DEC. 21, 1920.

56,964.

Patented Jan. 25, 1921.

Harold G. Fitzgerald, Inventor

By His Attorneys, Dodson & Roe

UNITED STATES PATENT OFFICE.

HAROLD G. FITZ GERALD, OF LOS ANGELES, CALIFORNIA.

DESIGN FOR A SPOT-LIGHT.

56,964.

Specification for Design.

Patented Jan. 25, 1921.

Application filed December 21, 1920. Serial No. 432,365. Term of patent 14 years.

To all whom it may concern:

Be it known that I, HAROLD G. FITZ GERALD, a citizen of the United States, residing at Los Angeles, in the county of Los Angeles and State of California, have invented a new, original, and ornamental Design for a Spot-Light, of which the following is a specification, reference being had to the accompanying drawing, forming part thereof.

The figure is a view in side elevation of my improved design applied to a spot light.

I claim:

The ornamental design for a spot light, as shown.

HAROLD G. FITZ GERALD.
